UNITED STATES PATENT OFFICE.

FRANK J. HENRY, OF KALAMAZOO, MICHIGAN.

SPRING-TOOTH HARROW.

SPECIFICATION forming part of Letters Patent No. 638,513, dated December 5, 1899.

Application filed April 30, 1897. Serial No. 634,616. (No model.)

To all whom it may concern:

Be it known that I, FRANK J. HENRY, of Kalamazoo, in the county of Kalamazoo and State of Michigan, have invented certain new and useful Improvements in Spring-Tooth Harrows; and I do hereby declare that the following is a full, clear, and exact description of the invention, which will enable others skilled in the art to which it appertains to make and use the same, reference being had to the accompanying drawings, and to the letters and numerals of reference marked thereon, which form part of this specification.

My invention has for its object certain improvements in spring-tooth harrows, which will be hereinafter more fully pointed out and claimed.

In the drawings forming a part of this specification, Figure 1 is a perspective view of a harrow with my improvements applied. Fig. 2 is a side view of a portion of the harrow-frame at the point where the bars are coupled together. Fig. 3 is a perspective view of one-half of the coupling-clip. Figs. 4, 5, 6, 7, 8, and 9 illustrate details of construction.

In the several figures of the drawings similar letters and numerals will refer to corresponding parts in the several views.

Having described my invention in general terms as illustrated in the figures, I will now proceed to describe in detail its construction and operation.

The frame of my harrow is constructed of substantially square or rectangle metal bars 1 2, placed in the frame diagonally, so as to form substantially diamond-shaped openings between the frame-bars, as best illustrated in Fig. 1. The frame-bars cross each other so that the two frame-bars are in contact with each other at the intersecting angles of the frame-bars, so that the angle of one bar will engage the angle of the other bar, as best illustrated in Figs. 2, 4, 5, 6, and 9, so that when the pressure is applied to the coupling-irons the intersecting angles of the bars impinge against each other in a way that prevents the frame-bars from sliding or moving in the coupling-irons.

In constructing the frame the same is so formed as to give the requisite and proper spaces of the teeth, so that the whole surface of the ground between its lateral extremities

will be cut when the harrow passes over the same.

The frame-bars 1 2 at their intersecting points are rigidly held in place to prevent sliding or working by what I term a "divided" frame-clip or coupling-iron 3 6. The lower half 3 of coupling-iron is provided with angular groove 3^a (best illustrated in Fig. 9) for receiving one of the angles of the frame-bar 1. This section of the coupling-iron is provided with bolt-holes a⁵ for the reception of bolts 5 5. (Best illustrated in Fig. 7.) Frame-bar 2 is placed in cross-grooves b³ b³, (best illustrated in Fig. 9,) the frame-bars being shown in dotted lines. Having thus located the bars in the lower half of the coupling-irons I place the upper half 6 of the coupling-iron, over the intersecting bars. Groove b⁶, Fig. 8, is placed astride of the intersecting angles of frame-bar 2 with frame-bar 1. The cross-grooves c⁶ (best illustrated in Fig. 8) engage the other frame-bar of the harrow, so that when bolts 5 5 are passed through openings a⁵ a⁵ and the nuts turned down the frame-bars are rigidly clamped together sufficiently tight to prevent their movement, their contact-points being rigid.

For the purpose of securing curved spring-teeth in position underneath the clips or coupling-irons I provide a substantially flat surface f on the lower face of the frame-clip or coupling-iron, (best illustrated in Figs. 6 and 9,) on the under side of the lower half of the coupling-iron, which fits inside of walls g g of tooth-clip g', Fig. 7, the tooth-clip being supported and held in place by tightening-bolts 5 5. The curved spring-tooth 20 is placed in tooth-clip g'. Walls g g, Fig. 7, of clip g' restrain the lateral movement of the tooth and also engage the opposing edges of clip 3. The opposing edges having flat surface f, project into the opening in clip g', Fig. 7, and prevent the parts from lateral movement, and by tightening the screw-threaded nuts on the tightening-bolts the two halves of the coupling-iron and the tooth are held in position in substantially the same vertical line of the parts. By this arrangement of parts the frame-bars are carried in a somewhat elevated plane above the tooth-clip, affording clearance between the harrow-frame and the ground.

For the purpose of gaging the depth of the

cut of the teeth in the soil and in carrying the frame and teeth out of contact with the ground in transporting the harrow I provide lever-mechanism-operating shoes, as herein-
 5 after more fully described. For this purpose I provide upwardly-extending brackets 4, which are secured by bolts 5 5 (best illustrated in Figs. 4, 5, and 6) in substantially the same vertical plane of the coupling-iron,clips, and tooth. In the upper free end of brackets 10 4 4 I mount turnable rod 7. (Best illustrated in the figures last named.) Connected rigidly to these turnable rods I attach shoes 8, which curve downward and rearward, so that they 15 may be elevated or depressed for the purposes heretofore stated. The turnable rods 7 in the brackets are operated by means of standards rigidly secured to the turnable rods operated on by lever 10, to which is connected a 20 spring-actuated dog 11, which engages ratchet 12, rigidly secured to connecting-bars 13 at the rear of the harrow, and at the front of connecting-rod 13 the same is connected with a standard or bracket 14, rigidly secured to 25 the turnable rod 15, mounted in front brackets 4 4, secured to the frame in substantially the same way as brackets illustrated in Figs. 4, 5, and 6 are attached. These front brackets carry, support, and allow to rotate turn- 30 able rod 16 in the front of the frame, to which turnable rod I attach rigidly shoe 17, deflected downward and rearward, as before stated.

The advantage of the construction herein 35 shown and described consists in having a lever-and-shoe mechanism supported on the frame in substantially the same vertical line with the coupling-irons, frame-bars, and tooth. I, however, do not limit myself to this distinctive feature, because the lever operating and 40 supporting mechanism may be located elsewhere on the frame, the distinctive feature being the application of the curved shoes on a lever-operating rocking bar where the shoe 45 or shoes operate within the frame, which has diamond - shaped or irregular openings between the frame - bars, which harrows are known and designated in the trade as the "A-shaped - frame" harrow—that is to say, 50 where the sections of the harrow when coupled as a whole present an angle at the front deflecting outward from the center point.

What I claim as new, and desire to secure by Letters Patent, is—

55 1. In a harrow the combination of the frame-bars crossing each other at an angle, curved spring-teeth located in the vertical line of the intersecting angles of the frame-bars, a tooth-clip, a bracket located on the upper surface 60 of the harrow-frame substantially at the vertical line of the intersecting angles of the

frame-bars, and brackets extending above the frame-bars and provided at their free ends with journals for receiving a turnable rod, a turnable rod journaled in the brackets 65 operated by lever mechanism and shoes rigidly secured to the turnable rods extending downward and rearward, substantially as set forth, for the purposes stated.

2. In a harrow the combination of the intersecting frame-bars engaging each other at their intersecting angles, a frame-clip composed of two intersecting and engaging sections arranged to clamp the frame-bars and to engage each other, a spring-tooth located 70 in a vertical line of the intersecting angles of the frame-bars, a tooth-clip, brackets located in substantially the same vertical line of the intersecting angles of the frame - bars, the bracket extending upwardly from the upper 75 surface of the frame and provided at their free ends with journals for receiving turnable rods, turnable rods journaled to the free ends of the brackets operated by lever mechanism, shoes rigidly secured to the turnable tooth- 80 bar extending downward and rearward, substantially as set forth, for the purposes stated.

3. In a harrow the combination of the frame-bars crossing each other at an angle, curved spring-teeth located in substantially a vertical line with the intersecting angles of the frame-bars, a tooth-clip provided with walls 85 g g, brackets located above the frame - bars provided with journals, the turnable rod journaled in the brackets operated by lever mechanism 90 and shoes rigidly secured to the turnable rods extending downward and rearwardly, substantially as set forth, for the purposes stated.

4. In a harrow, the combination of the intersecting frame-bars, the interlocking frame-clips, the curved spring-teeth, the tooth-clip, the bracket, arranged substantially in the same vertical line, and means for holding the parts together, substantially as set forth. 100

5. In a spring-tooth harrow, the combination of the intersecting frame-bars, the curved tooth mounted on the frame-clip below the horizontal line of the frame, the clip for securing the tooth on its seat, the frame-bracket, 105 provided with means for raising and lowering the harrow-frame, the various parts being arranged in substantially the same vertical line, with means for holding the various parts together for the purpose stated. 115

In witness whereof I have affixed my signature in presence of two witnesses.

FRANK J. HENRY.
